MULTIPLE DEFLECTION CATHODE-RAY
TUBE

Paul J. Selgin, Fort Wayne, Ind., assignor, by
mesne assignments, to Farnsworth Research
Corporation, a corporation of Indiana

Application February 1, 1947, Serial No. 725,828

12 Claims. (Cl. 250—27)

1

This invention relates to cathode ray tubes and particularly to that type of tube wherein an electron beam is deflected under the control of a signal over a target electrode structure whereby to effect signal modulation and/or amplification.

There are numerous cases where a cathode ray tube of the so-called deflection type may be used to a greater advantage than a conventional grid-controlled vacuum tube. In general, it is possible to achieve a higher ratio of mutual conductance to average input current in a cathode ray tube than in a grid-controlled vacuum tube, particularly at low signal levels. Likewise, by suitable electrode design, a cathode ray tube of the deflection type may be used to produce a greater linearity of response. Additionally, amplification of the deflected electron beam may be conventionally secured by the employment of an electron multiplier mounted in the same envelope with the cathode ray tube.

However, it is not always possible to secure the desired sensitivity when using a cathode ray tube as a signal amplifier, for example. In order to minimize signal distortion, it is necessary in many cases to develop an electron beam which has a relatively small cross-section. To produce such a beam and yet to maintain a relatively high order of electron concentration in the beam, it is necessary to produce a relatively high acceleration of the electrons. In this manner there is produced what is known as a stiff beam which is relatively difficult to deflect. Such a characteristic, however, is not advantageous when sufficient deflecting energy is available. But, where it is desired to utilize signal energy with a minimum of preamplification as the source of deflecting voltage, only a relatively small deflection of the electron beam is produced. It, therefore, is difficult to avoid introducing some distortion in the signal derived from the output circuit of the device when small beam deflections only are available.

It is an object of the present invention, therefore, to provide a cathode ray tube of deflection type which is capable of achieving a substantial deflection of the electron beam under the control of relatively small deflecting voltages.

Another object of the invention is to provide a cathode ray tube of the deflection type having an electrode structure and arrangement capable of producing a multiple deflection of an electron beam under the control of relatively small deflecting voltages, whereby to produce at least one beam deflection of substantial magnitude.

Still another object of the invention is to provide a novel method of signaling, utilizing a multiple deflection of an electron beam.

In accordance with this invention, there is

2

provided a cathode ray tube having means for developing an electron beam. The tube also is provided with a plurality of beam deflecting systems and a plurality of target electrode systems.

5 The deflecting systems and the target electrode systems are arranged alternately along the path of the beam. By means of the first one of the deflecting systems the beam is deflected over a succeeding target electrode system. A succeeding deflecting system is coupled to a target electrode system which precedes it, in order to effect another deflection of the beam.

The first target electrode system is constructed in such a manner that it is capable of intercepting only a portion of the electron beam. The unintercepted portion of the beam is deflected by means of a succeeding deflecting system over another target electrode system.

More specifically any one or all of the target electrode systems may include an electron multiplier. In such a case the electrode structure, which is impinged by the deflected beam, is a good emitter of secondary electrons. In cases where the first target electrode system includes an electron multiplier, the second deflecting system may be energized by coupling either to the secondary electron emissive electrodes, or to the electron collecting electrodes of the first target electrode system. In a preferred form of the invention all deflecting systems are energized in phase, so that the beam is deflected in the same direction by all deflecting systems. Accordingly, if the coupling of the second deflecting system is made to the electron collecting electrodes of the first target electrode system, the coupling of the respective deflecting electrodes must be made to the collecting electrodes which are located on the opposite sides of the beam path.

40 In accordance with the novel method of the present invention, a multiple deflection of an electron beam is effected. The initial deflection is effected under the control of a signal. Additional beam deflection is effected under the control of preceding deflections.

45 For a better understanding of the invention, together with other and further objects thereof, reference is made to the following description, taken in connection with the accompanying drawing, and its scope will be pointed out in the appended claims.

50 In the drawing, Fig. 1 is a diagrammatic illustration of a cathode ray tube embodying one form of the invention, together with sufficient circuit details to demonstrate one mode of operation of such a device; and

55 Fig. 2 is a fragmentary illustration of a detail of the first target electrode structure.

Having reference now to Fig. 1 of the drawing, the cathode ray tube is provided with an

evacuated envelope 11. An electron gun 12, shown diagrammatically, is mounted in one end of the tube envelope. The electron gun may be entirely conventional and develops an electron beam 13 which is projected toward the other end of the tube in which is located the target electrode structures. A pair of deflecting plates 14 is located adjacent the path of the beam. Also, there is provided a first target electrode structure located generally in the path of the beam and consisting of a pair of plate electrodes 15 mounted at an angle relative to the path of the beam. The plates 15 may be separate structures as shown, or if desired may be formed in a unitary structure. As illustrated herein, the two plates 15 are separated from one another, leaving an aperture in the path of the undeflected electron beam. Obviously, if the plates 15 are part of the unitary structure a similar suitable aperture may be provided. In the present case the plates 15 serve as dynode electrodes; that is, they are capable of emitting secondary electrons when impacted by a primary electron beam. Adjacent to the dynodes 15 is located a pair of electron collecting plates 16.

Farther along the path of the electron beam there is mounted a second deflecting system comprising a pair of parallel plates 17. Finally, there is provided a second target electrode structure consisting of a pair of dynodes 18 and a pair of electron collectors 19. In the illustrative embodiment of the invention, both target electrode systems are shown as similar structures, except that the second system need not be provided with the aperture required in the first system.

Such a cathode ray tube may be used in cooperation with a source of signals 21 for amplifying these signals and impressing them upon a utilization circuit 22. The signal source 21 is connected to an input resistor 23, the terminals of which are coupled to the plates 14 of the first deflecting system. The amplified signal effects are developed in an output resistor 24, the terminals of which are coupled to the electron collectors 19 and also to the utilization circuit 22.

The tube electrodes and auxiliary circuits are energized for operation by suitable connections, to be described, to a power source such as represented by a battery 25. The battery voltage is distributed to the tube electrodes and auxiliary circuits by a voltage divider 26 which is connected to the terminals of the battery. The grounded negative terminal of the power supply is connected to the source of electron emission forming a part of the electron gun 12 in a conventional manner. A somewhat more positive potential is impressed upon the first and second target electrode plates 15 and 18, respectively. The positive terminal of the power supply is connected to a center tap on both the input and output resistors 23 and 24, respectively. It also is connected to a center tap on a resistor 27, the terminals of which are connected to the collector electrodes 16 of the first target electrode structure. Finally, the plates 17 of the second deflecting system are coupled suitably to the collector electrodes 16 of the first target electrode system. As shown, the upper deflecting plate 17 is connected to the lower collector plate 16. Similarly, the lower deflecting plate is connected to the upper collector.

Before describing in detail the operation of the described device, a brief reference will be made to Fig. 2. This view is one in elevation of the first target electrode dynodes 15. The inner

edges of these two electrodes are serrated generally in the manner shown to form a series of spaced projections or teeth 28. Preferably the width of the teeth is maintained relatively small and the spacing between the teeth relatively large. The teeth are formed so that they will be deeper than the maximum deflection of the electron beam. By means of such a structure, the greatest portion of the electron beam, whether or not it is deflected, is not intercepted by the plates 15. However, a small percentage of the electron beam will be intercepted by the teeth 28, depending upon the magnitude of the beam deflection.

Referring now to the operation of the device, in accordance with the present invention, it will be assumed that a signal of suitable polarity is impressed upon the input resistor 23 to develop voltages at the first deflecting plates 14 of a character whereby to effect an upward deflection of the beam 13. As previously described, the major portion of this beam passes without interruption through the aperture formed by the toothed dynode plates 15. This portion of the electron beam will be considered subsequently.

By reason of the upward deflection of the beam there is intercepted by the teeth 28 of the upper dynode 15 a greater number of electrons than are intercepted by the teeth of the lower dynode 15. Consequently, a greater number of secondary electrons will be liberated from the upper plate than from the lower plate, and it follows that more electrons will be finally collected by the upper collector 16 than by the lower collector 16. Therefore, there is developed a voltage in the resistor 27 which is representative of the amount by which the beam is deflected. The potential of the lower collector is more positive than the upper collector and, since these two electrodes are cross-coupled to the second deflecting plates 17, this deflecting system also produces an upward deflection of the larger portion of the beam which is not intercepted by the first target electrode structure. A sufficient number of electron multiplying stages may be provided in the first target electrode structure to impress voltages of considerable magnitude upon the second deflecting system. By this means, then, a much greater deflection of the electron beam may be produced so that signal effects varying over a considerable range will be developed in the output circuit resistor 24. The beam deflection over the dynodes 18 is substantially similar to that described in connection with the dynodes 15.

It should be evident that, by amplifying the electron beam in the first target electrode structure where relatively small deflections are produced under the control of the signals, voltages of considerably increased magnitudes may be developed as representative of the signals for controlling the larger deflection of the beam by the second deflecting system. Thus, there is provided a device which has the desirable attributes of good linearity of response and a favorable ratio of mutual conductance to average input current and, at the same time, is capable of being energized by the signals having a minimum of preamplification.

It is to be understood that, while the invention is disclosed herein as having two deflecting systems and two target electrode systems, it is not necessarily so limited. Obviously, more than two beam deflections may be effected by providing additional deflecting systems and target electrode systems. The additional deflecting systems may

be coupled to a preceding target electrode system in accordance with the present disclosure.

While there has been described what at present is considered the preferred embodiment of the invention, it will be obvious to those skilled in the art that various changes and modifications may be made therein without departing from the invention, and it, therefore, is aimed in the appended claims to cover all such changes and modifications as fall within the true spirit and scope of the invention. 10

What is claimed is:

1. A cathode ray tube comprising, means for developing an electron beam, a plurality of beam deflecting systems, a plurality of target electrode systems, said deflecting systems and said target electrode systems being arranged alternately along the path of said beam, means including the first one of said deflecting systems for deflecting said beam over a succeeding target electrode system, and means coupling one of said succeeding deflecting systems to a preceding target electrode system for effecting another deflection of said beam. 15

2. A cathode ray tube comprising, means for developing an electron beam, a series arrangement along the path of said beam of a first deflecting system, a first target electrode system, a second deflecting system and a second target electrode system, said first target electrode system being constructed to intercept only a portion of said beam, and means coupling said second deflecting system to said first target electrode system for energizing said second deflecting system. 20

3. A cathode ray tube comprising, means for developing an electron beam, a series arrangement along the path of said beam of a first deflecting electrode system, a first target electrode system, a second deflecting electrode system and a second target electrode system, said first target electrode system having an aperture located in the undeflected path of said beam, whereby to permit passage of the major portion of said beam, and means coupling said second deflecting electrode system to said first target electrode system for energizing said second deflecting electrode system in phase with said first deflecting electrode system. 25

4. A cathode ray tube comprising, means for developing an electron beam, first means located adjacent to the path of said beam for effecting a first deflection of said beam, a pair of sampling target electrodes located behind said first deflecting means to intercept only a portion of said deflected beam, second means located behind and coupled to said sampling electrodes for effecting a deflection of the unintercepted portion of said beam, and a main pair of target electrodes located behind said deflecting means for respective impingement by said unintercepted beam. 30

5. A cathode ray tube comprising, means for developing an electron beam, means located adjacent to the path of said beam for effecting a first deflection of said beam, a pair of sampling target electrodes located behind said first deflecting means and each having such a configuration as to intercept only a portion of said deflected beam, a pair of deflecting electrodes located behind and coupled to said sampling electrodes for effecting a deflection of the unintercepted portion of said beam, and a main pair of target electrodes located behind said pair of deflecting electrodes for respective impingement by said unintercepted beam in proportion to the deflection thereof. 35

6. A cathode ray tube comprising, means for developing an electron beam, a first pair of deflecting electrodes located adjacent to the path of said beam for effecting a first deflection of said beam, a pair of sampling target electrodes located behind said first pair of deflecting electrodes and each having an uneven edge configuration, whereby to intercept only a portion of said deflected beam, a second pair of deflecting electrodes located behind said sampling electrodes and each being coupled to one of said pair of sampling electrodes for effecting a second deflection of the unintercepted portion of said beam, and a main pair of target electrodes located behind said second pair of deflecting electrodes for respective impingement by said unintercepted beam in proportion to said second beam deflection. 40

7. A cathode ray tube comprising, means for developing an electron beam, a first pair of deflecting electrodes located adjacent to the path of said beam for effecting a first beam deflection, a pair of sampling secondary electron emissive target electrodes located behind said first pair of deflecting electrodes and each having an uneven edge configuration, whereby to intercept a relatively small portion of said deflected beam, a pair of electron collecting electrodes located adjacent to said sampling electrodes, whereby to collect respectively secondary electrons in proportion to said first beam deflections, a second pair of deflecting electrodes located behind said sampling electrodes and each being coupled to one of said pair of collecting electrodes for effecting a second deflection of the unintercepted portion of said beam, and a main pair of target electrodes located behind said second pair of deflecting electrodes for respective impingement by said unintercepted beam in proportion to said second beam deflection. 45

8. A cathode ray tube comprising, means for developing an electron beam, a first pair of deflecting electrodes located adjacent to the path of said beam for effecting relatively small deflections of said beam, a pair of sampling target electrodes located behind said first pair of deflecting electrodes and having notched edges, whereby to intercept a relatively small portion of said deflected beam, a second pair of deflecting electrodes located behind said sampling electrodes and each being coupled to one of said pair of sampling electrodes for effecting relatively large deflections of the unintercepted portion of said beam corresponding to said relatively small deflections, a main pair of secondary electron emissive target electrodes located behind said second pair of deflecting electrodes for respective impingement by said unintercepted beam in proportion to said relatively large deflections, and a pair of electron collecting electrodes located adjacent to said main target electrodes, whereby to collect secondary electrons in proportion to said relatively large deflections of said unintercepted beam. 50

9. A cathode ray tube comprising, means for developing an electron beam, a first pair of deflecting electrodes located adjacent to the path of said beam and having potentials varying according to signals for effecting corresponding relatively small deflections of said beam, a pair of sampling secondary electron emissive target electrodes located symmetrically adjacent to the undeflected path of said beam and provided with serrated edges, whereby to intercept a relatively small portion of said deflected beam, a first pair 55

of electron collecting electrodes located adjacent to said sampling electrodes, whereby to collect respectively secondary electrons in proportion to said relatively small deflections of said beam, a second pair of deflecting electrodes located adjacent to the path of the unintercepted portion of said beam behind said sampling electrodes and each being coupled to one of said first pair of collecting electrodes for effecting relatively large deflections of said unintercepted beam corresponding to said relatively small deflections, a main pair of secondary electron emissive target electrodes located behind said second pair of deflecting electrodes for respective impingement by said unintercepted beam in proportion to said relatively large deflections, and a second pair of electron collecting electrodes located adjacent to said main target electrodes, whereby to collect secondary electrons in proportion to said relatively large deflections of said unintercepted beam.

10. A cathode ray tube comprising, means for developing an electron beam, a first pair of deflecting electrodes located on opposite sides of said beam and having potentials varying according to signals for effecting corresponding relatively small deflections of said beam, a pair of sampling secondary electron emissive target electrodes located on opposite sides of the undeflected path of said beam and provided with serrated inner edges, whereby to intercept a relatively small portion of said deflected beam, a first pair of electron collecting electrodes located respectively adjacent to said sampling electrodes, whereby to collect respectively secondary electrons in proportion to said relatively small deflections of said beam, a second pair of deflecting electrodes located on opposite sides of the unintercepted portion of said beam behind said sampling electrodes and each being connected to one of said first pair of collecting electrodes for effecting relatively large deflections of said unintercepted beam corresponding to said relatively small deflections, a main pair of secondary electron emissive target electrodes located adjacent to the undeflected path of said unintercepted beam for respective impingement by said unintercepted beam in proportion to said relatively large deflections, and a second pair of electron collecting electrodes located respectively adjacent to said main target electrodes, whereby to collect secondary electrons in proportion to said relatively large deflections of said unintercepted beam.

11. A cathode ray tube comprising, means for developing an electron beam, a first pair of deflecting electrodes located on opposite sides of said beam adjacent to said beam developing means and having potentials varying according to signals for effecting corresponding relatively small

deflections of said beam, a pair of sampling secondary electron emissive target electrodes located symmetrically on opposite sides of the undeflected path of said beam and provided with serrated centrally disposed edges, whereby to intercept a relatively small portion of said deflected beam, a first pair of electron collecting electrodes located respectively adjacent to said sampling electrodes, whereby to collect respectively secondary electrons in proportion to said relatively small deflections of said beam, a second pair of deflecting electrodes located on opposite sides of the unintercepted portion of said beam behind said sampling electrodes and each being connected to the one of said first pair of collecting electrodes located on the opposite side of said beam for effecting relatively large deflections of said unintercepted beam corresponding to said relatively small deflections, a main pair of secondary electron emissive target electrodes located symmetrically adjacent to the undeflected path of said unintercepted beam for respective impingement by said unintercepted beam in proportion to said relatively large deflections, and a second pair of electron collecting electrodes located respectively adjacent to said main target electrodes, whereby to collect secondary electrons in proportion to said relatively large deflections of said unintercepted beam.

12. A signaling system comprising, a source of signals, a utilization circuit, a cathode ray tube including means for developing an electron beam, a plurality of deflecting electrodes, a plurality of target electrodes, said deflecting and target electrodes being arranged alternately along the path of said beam, means for coupling a first pair of deflecting electrodes to said signal source for effecting an initial deflection of said beam over a succeeding target electrode, means for developing at said target electrodes voltages representative of the beam deflections over said target electrodes, means for coupling succeeding deflecting electrodes to preceding target electrodes in proper polarity for effecting other deflections of said electron beam corresponding in sense to said initial deflection, and means for impressing upon said utilization circuit the voltage developed at the final target electrode.
